UNITED STATES PATENT OFFICE.

JOSEPH BOMGARDNER, OF BEREAL, OHIO.

DESIGN FOR A CASKET-LOWERING FRAME.

SPECIFICATION forming part of Design No. 33,869, dated January 8, 1901.

Application filed September 6, 1900. Serial No. 29,234. Term of patent 14 years.

To all whom it may concern:

Be it known that I, JOSEPH BOMGARDNER, a citizen of the United States, residing at Berea, in the county of Cuyahoga and State of Ohio, have invented and produced a new and original Design for Casket-Lowering Frames, of which the following is a specification, reference being had to the accompanying drawing, forming a part thereof.

The figure is a perspective view of the frame.

As shown in the drawing, the leading or material feature of my design consists of a casket-frame the end members of which are angular in cross-section and the side members thereof circular in cross-section.

The end member 1 is provided with the laterally-extending portion 2, upon the top or upper side of which is formed a raised extension 3. The end member 1 is provided with the V-shaped opening 4, located about midway between the side members 5 and 6. Each of the side members is provided with the raised flanges 7, said flanges being located and arranged substantially as shown, and as shown they are located around openings 8, which openings are formed in the inner sides of the side members 5 and 6. The inner end of the laterally-extending portion 2 is provided with the L-shaped flange 9, said L-shaped flange being located substantially as shown in the drawing. Upon the top or upper

side of the side member 5 is formed a flange 4^a, upon which flange is located a circular head 5^a. The end member 10 is substantially 35 of the form shown and is provided with the rounded ends 11, which rounded ends correspond substantially with the curvature of the circular side members 5 and 6. The end member 1 is provided with the circular aperture 12, and the lateral extension 2 is provided with the flange 13. The end member 1 is also provided with rounded ends, the curvature of which, together with the curvature of the lateral extension 2, corresponds substantially 45 with the curvature of the circular side members 5 and 6. Upon the outer side of the end member 1 and near the aperture 12 is located the flange 14, which flange is formed as shown and is located between the aperture 50 12 and the V-shaped opening 4.

Having fully described my invention, what I claim as new, and desire to secure by Letters Patent, is—

The design for a casket-lowering frame as 55 herein shown and described.

In testimony that I claim the above I have hereunto subscribed my name in the presence of two witnesses.

JOSEPH BOMGARDNER.
